UNITED STATES PATENT OFFICE

148,550

DESIGN FOR A TRUCK BODY

Raymond Loewy, New York, N. Y., assignor to The Coca-Cola Company, Wilmington, Del., a corporation of Delaware

Application July 5, 1946, Serial No. 131,545

Term of patent 14 years

(Cl. D14—3)

To all whom it may concern:

Be it known that I, Raymond Loewy, a citizen of the United States and resident of New York, New York County, New York, have invented a new, original, and ornamental Design for a Truck Body, of which the following is a specification, reference being had to the accompanying drawings, forming part thereof.

Fig. 1 is a side perspective view of a truck body showing my new design;

Fig. 2 is also a perspective view; and

Fig. 3 is a rear elevational view thereof.

The dotted line showing in the several figures of the drawings is for illustrative purposes only.

I claim:

The ornamental design for a truck body, as shown.

RAYMOND LOEWY.
